SMOKER'S PIPE

Jerome Gevirman, Brooklyn, N. Y.

Application February 18, 1955, Serial No. 34,580

Term of patent 14 years

(Cl. D85—8)

FIG-1.

FIG-4.

FIG-2.

FIG-3.

Fig. 1 is a top plan view of a smoker's pipe, showing my new design;

Fig. 2 is a side elevational view thereof;

Fig. 3 is a bottom plan view thereof; and

Fig. 4 is a fragmentary perspective view thereof, to an enlarged scale and partly in cross-section, taken on line 4-4 in Fig. 1.

I claim:

The ornamental design for a smoker's pipe, as shown.
